(57) **CLAIM**

The ornamental design for a stretchable torso wrap for securing catheter tubes on a patient, as shown and described.

DESCRIPTION

FIG. 1 illustrates a top perspective view of a stretchable torso wrap for securing catheter tubes on a patient showing our new design;

FIG. 2 illustrates a top plan view thereof;

FIG. 3 illustrates a bottom plan view thereof;

FIG. 4 illustrates a side elevation view thereof;

FIG. 5 illustrates a front elevation view thereof;
FIG. 6 illustrates a top perspective view of the stretchable torso wrap being oriented for placement over a single catheter tube secured on a patient's torso;

FIG. 7 illustrates a top perspective view of the single catheter tube being inserted into a first slit of the stretchable torso wrap;

FIG. 8 illustrates a top perspective view of the single catheter tube being pulled out of a second slit of the stretchable torso wrap; and,

FIG. 9 illustrates a top perspective view of the stretchable torso wrap placed over a patient's torso wrapped over the single catheter tube secured by the torso wrap.

The broken line showing of parts of the drawings is included for the purpose of illustrating portions of the "article" and forms no part of the claimed design.

1 Claim, 6 Drawing Sheets
